REFLECTOR

Edward A. Muller, Kew Gardens, N. Y.

Application September 12, 1938, Serial No. 229,592

2 Claims. (CL 240—103)

My invention relates to reflectors and more particularly to reflectors adapted to be secured about electric bulbs and the like.

One of the principal objects of my invention is to provide a reflector so constructed and arranged as to reflect light rays over a desired area and at the same time present an attractive and ornamental appearance.

Another object of my invention is to provide a reflector of the above described character which is simple in construction, durable in use, efficient in operation and economical in manufacture.

A special object of my invention is to provide a reflector of the character described which is especially adaptable for support about an electric bulb whereby to reflect rays of light from said bulb over a desired area for photographic purposes.

Other objects and advantages will be apparent from the following description, appended claims and annexed drawing.

Referring to the drawing wherein like reference characters designate like parts throughout the several views:

Figure 1 is a top plan view of the blank from which my reflector is formed.

Figure 2 is a sectional view taken on the line 2—2 of Figure 1.

Figure 3 is a side elevation of my improved form of reflector illustrating the same as attached about an electric lamp bulb of the Christmas tree type.

Figure 4 is a top plan view of my invention.

Figure 5 is a side elevation of a modified form of my invention.

In practicing my invention, in the preferred embodiment illustrated in Figures 1 to 4, I provide a frustum-shaped body constituting a reflector 5 and which is fashioned with an open bottom, closed top 6 and a fluted skirt 7 formed with a plurality of light emitting openings 8 therein. The top 6 is formed with a centrally disposed aperture 9 and is provided with pairs of oppositely disposed and radially extending slits 10 communicating with the aperture 9 and terminating at their outer ends at the jointure of the skirt with the top. The aperture embraces a socket 11 inserted therethrough and to which is secured an electric Christmas tree bulb 12 or the like. The radially extending slits provide yieldable fingers 14 therebetween for engaging the socket 11 to maintain the reflector suspended from the latter about the bulb.

The body is constructed of a centrally disposed

layer 15 of paper stock having on the outer side thereof a layer 16 of foil, the latter being suitably lacquered to provide scintillation. The opposite side of the centrally disposed layer 15 is provided with a layer 17 of foil, the latter being preferably of aluminium and which constitutes the inner reflecting surface of the reflector when secured about the electric lamp bulb.

The initial step in the fabricating of my reflector consists of providing a body of material 10 of the foregoing construction and in the form of a disk, with the centrally disposed aperture 9 and radially extending slits 10 which terminate at their outer ends on a fold line 18.

When the disk is thus fashioned the latter is 15 radially fluted outwardly from the fold line 18, which extends circumferentially about the outer ends of the slits 10, and the fluted section or skirt is worked downwardly relative to the top to assume a substantially frustum-shaped configuration in side elevation as clearly illustrated 20 in Figure 3 of the drawing. The openings in the skirt permit light rays to be emitted therefrom and be reflected from other objects on a Christmas tree and thereby present a novel and attractive appearance.

In the modified form of my invention illustrated in Figure 5, the skirt 30 while being fluted is not provided with the openings therein as in the instance of the preferred embodiment there- 30 by providing an efficient collapsible reflector for use in photography and the like.

Furthermore, my device serves to reflect light rays from a light source over a desired area to enhance the novel and attractive appearance of 35 the tree.

What I claim is:

1. A reflector comprising a hollow body fashioned with a skirt having a transverse wall extending across one end of said skirt and formed 40 structurally integral with the skirt, said wall formed with a centrally disposed socket receiving opening and with spaced slits extending from said opening and terminating at the jointure of the skirt with said wall and with said slits defining therebetween fingers, said fingers being normally disposed in a common plane and having opposed end faces adapted to contiguously surround the periphery of a socket disposed through said opening to maintain contiguosity of the 45 fingers throughout their entire length to preclude light rays projecting through said slits from a light source carried by said socket and disposed within said skirt, said body formed with a centrally disposed layer of paper stock faced with 50 55

inner and outer layers of foil for reflecting light rays from within and without said body respectively with said inner and outer layers coating with said centrally disposed layer to reenforce 5 said fingers at said jointure with said skirt.

2. A reflector comprising a hollow body fashioned with a skirt and a transverse wall extending across one end of the body and formed structurally integral with the skirt, said wall formed 10 with a centrally disposed socket receiving opening and with spaced slits extending from said opening and terminating adjacent said skirt and with said slits defining therebetween fingers, said fingers being normally disposed in a common 15 plane and having opposed end faces adapted to contiguously surround the periphery of a socket disposed through said opening to maintain contiguity of the fingers throughout their en-

tire length to preclude light rays projecting through said slits from a light source carried by said socket and disposed within said skirt, said fingers having a definite bendable jointure with said body adjacent said skirt to permit displacement of said fingers out of said plane to effect insertion and withdrawal of the socket from said opening, said body formed with a centrally disposed layer of paper stock faced with inner and outer layers of foil for reflecting light rays from within and without said body respectively and with said inner and outer layers transversing said jointure for reinforcing the latter and enclosing said centrally disposed layer including the jointure whereby to minimize severance of the fingers from said body due to frequent displacement.

EDWARD A. MULLER.
